WIRE BAR AND PROCESS FOR MAKING
SAME

Karl A. Lindner, Baltimore, Md., assignor to
American Smelting and Refining Company,
New York, N. Y., a corporation of New Jersey

Application February 5, 1936, Serial No. 62,394

6 Claims. (Cl. 29—160.4)

This invention relates to the production of metal castings of the type ordinarily referred to as wire bars and more particularly to a process for treating said bars and the improved product provided thereby.

In casting copper wire bars, for example, which generally are from four inches to five inches in width and depth and from, say, fifty to sixty inches in length, the copper is cast in horizontal open faced molds with the result that the upper surface of the casting becomes oxidized. In addition to having a higher oxygen content than the remainder of the casting this set surface is wrinkled and upon subsequent rolling and fabrication imperfections appear in the finished product.

In order to overcome these defects it has been proposed to cast the bars in vertical molds but such practice has not effectively solved the problem by reason of the fact that vertical casting itself is an expensive operation and the bars produced thereby are subject to deep piping.

It has also been proposed to remove the oxidized surface on the horizontal cast bars by subjecting the castings to a simple milling or planing operation but this practice also has failed to satisfactorily solve the problem principally by reason of the fact that sharp broken edges are left by the cutting tools and the sharp right angles at the edges of the bar are the source of various slivers in the subsequent working operations.

The present invention provides a process for treating horizontally cast bars which eliminates entirely the defects heretofore noted and provides an improved bar which precludes imperfections in the final product. In general the invention provides for milling the oxidized surface of the bar and removing the rough and irregular edges to produce a bar having smooth, rounded or beveled edges extending substantially the entire length of the bar.

The invention and the manner of practicing the same will be more readily understood by reference to the accompanying drawings, in which

Fig. 1 is a side elevation of a machine suitable for practicing the invention, the view illustrating the directions of movement of the bar during treatment and also the extent of such movement;

Fig. 2 is a plan view of the machine of Fig. 1;

Fig. 3 is an end elevation of the machine, the wire bars mounted thereon being shown in section, the view illustrating the arrangement and

disposition of the cutters employed in operating upon the bars;

Fig. 4 is an enlarged detailed view showing the manner of clamping the bars in position and the arrangements of the cutters operating upon the bars, the view being taken generally along the line 4—4 of Fig. 1 looking in the direction of the arrows;

Fig. 5 is a top plan view of a mold for horizontally casting the wire bars;

Fig. 6 is a cross-section taken along the line 6—6 of Fig. 5;

Fig. 7 is a perspective view of a horizontally cast wire bar;

Fig. 8 is a cross-section taken along the line 8—8 of Fig. 7;

Fig. 9 is a perspective view of an improved wire bar of the present invention; and

Fig. 10 is a cross-section taken along the line 10—10 of Fig. 9.

Referring more particularly to the drawings, the machine embraces a base 1, upon which is mounted an oscillatable work table or carriage 2, upon which the bars may be mounted in pairs, and which is operated in any usual manner. This table is provided with clamping and straightening devices 3, 3 which are adapted to clamp and straighten the wire bars 4 adjacent to their ends and to carry the wire bars 4 between a pair of motors 5, 5. The wire bars 4 as they go to the machine are of the usual shape, having tapered ends 23 and set surface 43 with the portion of the bars intermediate the ends having substantially parallel sides. The limits of travel of the wire bars are indicated by the positions of the bar shown in Fig. 1, and the direction of travel of the bar is shown by the arrows 6, 6 in Fig. 1, it being clear from this figure that the bar is moved from its full line position to the dotted line position indicated in Fig. 1 and then back again to its full line position, these operations being repeated as many times as is necessary to impart the desired shape to the bar. The clamping and straightening devices 3, 3 are operated from air cylinders 7, 7 in the usual manner.

The motors 5, 5 are shown as inclined toward each other, the distance between the motors being adjustable by means of the mechanism shown in Fig. 3, comprising gears 8, 8 meshing with worms 9, 9 on each end of shaft 10, which shaft is operated by means of the hand wheels 11, 11 on the end of the shaft. Gears 8, 8 are mounted on shafts 12, 12 secured in the motor mountings

13, 13 and upstanding therefrom. The shaft 10 also serves as a brace to maintain the motors in the desired position of adjustment. Each mounting 13 is slidably positioned in the base 1 5 on guides 13a, 13a.

Each motor is provided with a sprocket 14, mounted on the drive shaft 15 of the motor, the pinion 14 meshing with a standard type of speed reducing gearing 16 which is enclosed in housing 17, and which drives a shaft 18 extending through the motor mounting 13, the shaft 18 having mounted thereon a milling cutter 19 which is adapted to operate upon the flat oxidized surface of the wire bar 4 to remove the 10 layer of oxide from the surface. During this 15 operation, of course, the table or carriage 2 upon which the wire bars are mounted is travelling towards the cutter so that the wire bar will be moved continuously relatively to the cutter in 20 operative engagement therewith so that a uniform planing of the bars will be effected. When 25 the wire bars are moved from the full line position of Fig. 1 into the dotted line position of Fig. 1, the direction of travel of the carriage 2 is automatically reversed so that the wire bars mounted 30 on the carriage are moved back into engagement with the milling cutters 19, this operation being repeated until the oxide surface has been completely removed.

30 It will be observed from the drawings that operating in conjunction with the milling cutters 19 are radial or edge cutters 20, 20; these cutters being mounted in pairs for operating on the sharp edges of the wire bars produced by 35 the cutters 19. These cutters are mounted in pairs on shafts 21, 21 which are suitably driven by the respective motors. These cutters 20, 20 round off or bevel the sharp, irregular edges produced by the cutters 19, 19 and cut the edges 40 of the bar so as to produce a rounded or beveled surface of such depth that all the aforesaid irregularities are completely removed, leaving the bar with the rounded or beveled edges 22, 22 extending the full length of the bar, including 45 the tapered ends 23, 23 thereof, as will be clearly apparent from Fig. 5. The depths of the various cuts on the bars will be determined by the adjustment of the motors 5, 5. The work table or carriage 2 moves along spindles 24, 24 suitably 50 positioned in the base 1.

The metal chips from the cutters drop into trough shaped recesses 25, 25 where they are collected. A chip conveyor, not shown, may operate in these recesses 25, 25 to convey the 55 chips to the end of the machine for further disposal.

It will be noted that each of the clamping vises 3 embraces the parts 26 and 27 engaging adjacent sides of the wire bars 4, 4 as will be apparent from Fig. 4 and cooperating with these parts 60 26 and 27 are the pins 28, 28 mounted in the ends of a yoke 29, which is adjustable by air pressure so as to cause pressure to be exerted upon the wire bars by the pins 28 so that each 65 wire bar 4 will be straightened and tightly clamped against the clamping surfaces 26 and 27. These clamping members 26 and 27 desirably have their surfaces notched or milled as indicated at 30 for preventing the wire bars from slipping during the cutting operations. The 70 clamping pins 28, 28 are threaded as indicated at 31, and are held in position by a nut 32 screwed down on the threads 31.

75 Again referring to the radial cutters 20, it

will be understood that any suitable driving mechanism for these cutters may be used. One form of such mechanism is illustrated more or less diagrammatically in the drawings, and is shown as comprising a worm gear 33 mounted 5 upon the shaft 18, the gear 33 meshing with a worm 34 on one end of a horizontally extending shaft 35, the other end of which also is provided with a worm 36, meshing with a gear 37 on the upper end of the shaft 21 upon which radial cutters 20, 20 are mounted. This drive mechanism is duplicated for both motors, as is obvious.

It will be noted that the cutters 20, 20 are splined on the shaft 21 so that they may move toward or away from each other longitudinally 15 of the shaft in conformity with the shape of the wire bar 4. In order to enable these cutters to follow the tapered ends of the bar, recessed collars 38, 38 are provided on the shaft 21 between the bearings 39, 39 and the cutters 20, 20. Relative movement of these cutters on the shaft 21 to follow the configuration of the wire bar is obtained by timely manipulation of the forked members 40, 40 engaging collars 38, 38 by any suitable means, thus permitting the edges of the 25 bar to be rounded or beveled for the entire length thereof as shown in Fig. 5.

It will readily be appreciated by those skilled in the art that the wire bars of the present invention offer distinct advantages over the ordinary wire bars which are horizontally cast in molds of the type shown in Figs. 5 and 6 in which 30 41 represents the mold and 42 the cavities therein, and utilized without being treated in accordance with the present invention.

In addition to copper wire bars, the invention may be applied to castings of brass, aluminum, or other non-ferrous metals where the casting is to be subjected to subsequent hot or cold working operations.

This application is a continuation-in-part of 40 Karl A. Lindner, Serial Number 746,114, filed September 29, 1934.

What is claimed is:

1. A process for preparing copper wire bars 45 with tapered ends for subsequent working operations which comprises horizontally casting the bars, milling off the usual oxidized surface of the bar, and further milling off sharp, irregular edges along substantially the entire length of the bar 50 including the tapered ends to prevent formation of surface imperfections in the finished product resulting from the subsequent working of the bar.

2. The process for producing copper wire bars with tapered ends for subsequent working operations which comprises casting the wire bars, straightening said bars and substantially immediately thereafter milling the oxidized surface of the bar and the resulting irregular edges of the bar along substantially its entire length including 55 the tapered ends thereby preventing later formation of surface imperfections in the finished product by subsequent working of the bar.

3. The process for producing an improved copper wire bar with tapered ends which comprises 60 casting the wire bar in a horizontal mold in the usual manner, straightening said bar, milling off the oxidized surface of the cast bar and further milling the sharp edges along the sides of the 65 milled surface including the tapered ends to yield rounded or beveled edges extending substantially the entire length of the finished casting.

4. A milled copper wire bar having substantially parallel sides and tapered ends, all edges 70 75

thereof being smoothed and beveled for substantially the entire length of the bar including the tapered ends.

5. A copper wire bar having substantially parallel sides and being tapered at both ends, said bar having the set surface milled therefrom and having its edges rounded for the entire length of the bar including the tapered ends.

6. A horizontally cast, milled copper wire bar having substantially parallel sides and tapered ends, said bar being free from set and having the edges which bordered the set surface of the casting rounded or beveled for substantially the entire length of the bar including the tapered ends. 5

KARL A. LINDNER.
